UNITED STATES PATENT OFFICE

ANDREW NIEMI, OF HANCOCK, MICHIGAN

BOOT TREE

Application filed February 10, 1931. Serial No. 514,862.

The invention relates to improvements in forms used in the manufacture of boot legs having no seams at the rear, and it is the object of the invention to provide a form of this character having a number of improved characteristics.

With the foregoing in view, the invention resides in the novel subject matter herein-after described and claimed, description being accomplished by reference to the accompanying drawings.

Fig. 1 is a side elevation, the boot leather being shown in dotted lines.

Fig. 2 is a front elevation, the leather being shown in full lines upon the tree or form.

Fig. 3 is a central vertical longitudinal sectional view.

Fig. 4 is a longitudinal sectional view at right angles to Fig. 3.

Fig. 5 is a rear elevation.

Fig. 6 is a horizontal sectional view on line 6-6 of Fig. 3.

Fig. 7 is a perspective view showing details of construction used at the upper end of the tree or form.

Fig. 8 is a perspective view of one of the filler strips which may be used between the front and rear sections of the form.

Fig. 9 is a detail perspective view showing the heel form.

Fig. 10 is a detail perspective illustrating the instep form.

A preferred construction has been illustrated in the accompanying drawings and will be rather specifically described, with the understanding however, that within the scope of the invention as claimed, variations may be made.

An expandible leg form L is shown having a forwardly projecting instep form I and provided also with a heel form H, both forms I and H being detachable from the leg form L, in order that instep and heel forms of different dimensions may be substituted when required.

The leg form L is divided into front and rear sections F and R respectively, and the upper and lower end faces of said sections, 50 are formed with parallel undercut grooves

12. Plates 13 lie against the aforesaid end faces of the sections F and R and are provided with dove-tail ribs 14 which are slidably received in the grooves 12, said plates 13 being formed with central openings 15. Vertical screws 16 pass rotatably through the openings 15 and are rotatably mounted in bearing blocks 17 which are slidably seated in recesses 18 formed in the adjacent sides of the form sections F and R. Also formed in these sides of the sections F and R, are longitudinal wedge-ways 19 in which wedges 20 are slidably received, the screws 16 being threaded through said wedges respectively. By operating the upper screw, the upper ends of the form sections F and R may be spread to any desired extent, independently of the lower ends of said sections. Similarly, by operating the lower screw, the lower ends of said sections may be spread without similarly moving the upper ends of the sections.

Filler strips 21 are interposed between the sections F and R of the leg form and are provided in their ends with undercut notches 22 slidably receiving the ribs 14. Any desired number of these filler strips may be employed, or for unusually small boots, all of them may be removed.

The instep form I is dove-tailed to the front leg section F as shown at 22^a, being detachably secured by screw 23 (Fig. 3). The crest of this instep form I, and the front of the leg section F are formed with registering longitudinal grooves 24 and 25, in which a flat metal strip 26 is snugly seated, the upper portion of said strip 26 being secured to the leg section F by a screw 27, while the lower portion of said strip is secured by another screw 28 to the instep form I. By removing the screws 28 and 23, the instep form I may be downwardly slid from the leg form, whereupon another instep form of desired proportions may be substituted.

The strip 26 is provided with a plurality of spurs 29 spaced apart longitudinally thereof and adapted for passage through the overlapped edges 30 of the boot-forming leather or other material 31. These spurs thus not only anchor the overlapped edges of the material, but form the same with 100

openings to later receive eyelets or the like.

To prevent accidental pulling of the edges 30 from the spurs 29, a clamping strip 32 is employed, said clamping strip having its lower end hinged at 33 to a plate 34, the latter being detachably secured by a screw or the like 35 to the lower side of the instep form I. Strip 32 extends along the crest of the form I and vertically in front of the leg section F, and is provided with openings 36 which receive the projecting ends of the spurs 29. The upper end of the strip 32 is formed with a vertical slot 37 through which the flat head 38 of a clamping screw 39 may pass, said screw being threaded through the upper end of the strip 26. By turning the screw 39 retrogradely to loosen it and then disposing its head 38 vertically, the strip 32 may be forwardly swung to released position, the slot 37 then clearing said head 38.

When detaching the instep form I for substitution of another, the plate 34 is detached from said instep form and is attached to the form to be substituted, detachment and reattachment of said plate 34 being effected by means of the screw or the like 35.

The heel form H preferably embodies a block 40 secured within the bight portion of a U-shaped metal plate 41, the ends of said plate constituting forwardly projecting wings 42. The upper end of the block 40 abuts the lower end of the leg section R and is provided with an upstanding stud 43, said lower end of section R being formed with a downwardly opening socket 44 which removably receives said stud. The lower end of block 40 projects below the plate 41 and is provided with ears 45 to which the lower end of a rear clamping strip 46, is hinged at 47. This strip 46 extends vertically at the rear of the section R and is provided with releasable clamping means 47 at its upper end, similar to the clamping means for the front strip 32.

The heel form H may be readily detached from the leg section R and replaced with a heel form of other required dimensions, and when so doing, the clamping strip 46 is detached from the one heel form and attached to the substitute form.

The spurs 29 and the front and rear clamping strips 32 and 46, serve to hold the leather or the like 31 against the form, so that upon operation of the screws 16 and consequent spreading of the sections F and R, said material may be stretched to the required extent. If desired, a spring-contacted band 48 may be employed to assist in holding the upper end of the leg being formed from the material 31. Any desired number of the filler strips 21 may be employed, or they may all be omitted as desired, and instep and heel forms I and H of desired dimensions and proportions, may be used. Hence, boot legs of desired sizes and shapes and having instep

and heel portions of proper dimensions, may be readily formed with the improved tree, and due to the spurs 29, the front edges of the leg and instep portions will be provided with openings for eyelets or the like.

The rear clamping strip 46 is preferably provided with a measuring scale as seen in Fig. 5. The part 49 shown at the lower end of this strip is merely a spring which assists in outwardly swinging the strip 46 about the hinge 47.

Attention is again invited to the fact that variations may be made within the scope of the invention as claimed.

I claim:—

1. A boot leg-shaping form divided vertically into front and rear sections, the upper and lower end faces of said sections being provided with grooves, plates lying slidably against said upper and lower end faces of said sections and provided with ribs slidably received in said grooves, said plates having openings, and means for spreading said sections, embodying actuators passing through said openings.

2. A boot leg-shaping form divided vertically into front and rear sections, the upper and lower end faces of said sections being provided with grooves, plates lying slidably against said upper and lower end faces of said sections and provided with ribs slidably received in said grooves, said plates having openings, a filler section between said front and rear sections having notches in its ends slidably receiving said ribs, and means for spreading said front and rear sections, embodying actuators passing through said openings.

3. A boot leg-shaping device comprising an expandible leg form having a heel-shaping portion and a forwardly projecting instep form, a front clamping strip hinged at its lower end to the front extremity of said instep form, said strip extending along the crest of said instep form and vertically along the front of said leg form, a rear clamping strip hinged at its lower end to the lower part of said heel-shaping portion and extending vertically along said leg form, and releasable clamping means for securing the upper ends of said strips to said leg form.

4. A boot leg-shaping device comprising an expandible leg form having a forwardly projecting instep form, a row of spurs extending along the crest of said instep form and vertically along said leg form, said spurs being adapted for passage through overlapped front edges of the boot leg material to anchor said edges and form eyelet openings therein, and means for holding said overlapped edges against accidental pulling from said spurs.

5. A boot leg-shaping device comprising an expandible leg form provided with a forwardly projecting instep form, a row of projecting spurs extending along the crest of said

instep form and vertically along the front of said leg form, said spurs being adapted for passage through overlapped front edges of the boot leg material, a clamping strip extending vertically along said front of said leg form and forwardly along said crest of said instep form, said strip having openings to receive the ends of said spurs, and means for connecting the ends of said strip with 10 said leg and instep forms respectively.

6. A boot leg-shaping device comprising an expandible leg form provided with a forwardly projecting instep form, a row of projecting spurs extending along the crest of said 15 instep form and vertically along the front of said leg form, said spurs being adapted for passage through overlapped front edges of the boot leg material, a clamping strip extending vertically along said front of said leg 20 form and forwardly along said crest of said instep form, said strip having openings to receive the ends of said spurs, means hingedly connecting the lower end of said strip to said instep form, and releasable clamping 25 means for connecting the upper end of said strip with said leg form.

7. A boot leg-forming device comprising an expandible leg form, a detachable instep form projecting forwardly from said leg 30 form, the crest of said instep form and the front of said leg form having registering longitudinal grooves, a metal strip seated in said grooves, and means securing said strip to said leg and instep forms, but allowing detachment of said instep form.

8. A structure as specified in claim 7; together with outwardly projecting spurs rigidly carried by said strip.

9. A boot leg-shaping device comprising an 40 expandible leg form, a heel form abutting the lower end of said leg form and having forwardly projecting wings, and means detachably securing said heel and leg forms together.

45 10. A boot leg-shaping device comprising an expandible leg form, and a heel form abutting the lower end of said leg form and having an upstanding stud, said leg form having a socket removably receiving said stud.

50 11. A boot leg-shaping device comprising an expandible leg form, a heel form abutting the lower end of said leg form and detachably connected therewith, a clamping strip hinged to said heel form and extending upwardly along said leg form, and releasable 55 securing means for the upper end of said strip.

60 12. A boot leg-shaping device comprising an expandible leg form, a U-shaped heel-shaping plate at the lower end of said leg form, a 65 filler block secured within the bight portion of said U-shaped plate and abutting the lower end of said leg form, the latter having a downwardly open socket in said lower end, said block having an upstanding stud and a

downwardly projecting ear, said stud being received in said socket, a clamping strip hinged to said ear and extending vertically along said leg form, and releasable securing means for the upper end of said strip.

In testimony whereof I affix my signature. 70
ANDREW NIEMI.
